GYPSY MOTH TRAP

Morris William Kuchenbecker, Neenah, and Russell John Cook, Appleton, Wis., assignors to American Can Company, Greenwich, Conn.

Filed July 19, 1972, Ser. No. 273,276

Term of patent 14 years

Int. Cl. D22—05

U.S. Cl. D22—19

The figure is a perspective view of the gypsy moth trap of this invention, said trap being symmetrical about its longitudinal axis and having a planar bottom surface.

We claim:

The ornamental design for a gypsy moth trap, as shown and described.
